INVENTOR

Geo. W. Stafford

UNITED STATES PATENT OFFICE.

GEORGE W. STAFFORD, OF PROVIDENCE, RHODE ISLAND, ASSIGNOR TO THE
GEO. W. STAFFORD MANUFACTURING COMPANY, OF SAME PLACE.

SHEDDING MECHANISM FOR LOOMS.

SPECIFICATION forming part of Letters Patent No. 415,686, dated November 19, 1889.

Application filed August 5, 1889. Serial No. 319,803. (No model.)

To all whom it may concern.

Be it known that I, GEORGE W. STAFFORD, of Providence, in the county of Providence and State of Rhode Island, have invented certain new and useful Improvements in Sheding Mechanism for Looms; and I do hereby declare that the following is a full, clear, and exact description thereof, reference being had to the accompanying drawings, and to the letters of reference marked thereon, which form a part of this specification.

This invention refers to dobby mechanism for operating the heddle frames or harnesses of looms, and it is more particularly an improvement on the form of dobby shown in United States patent of August 21, 1888, No. 388,318, though it is applicable to positive-motion dobbies.

These improvements consist, mainly, in a modification of the pawl mechanism that operates the pattern-cylinder, and also of the plate-levers that are raised by the pins in the pattern-chain, whereby the pattern-chain for any particular pattern can be shortened; and also in a modification of the mode of pivoting the jack-levers on the harness-levers to maintain the position of the lower latch-hooks when they are not in motion, and allow of a relative increase of the motion of the harness-levers.

In the drawings, Figure 1 shows a front elevation, partly in section, of the working parts of the dobby, the frame being left out. Fig. 2 is a top view of the ratchet-wheels on the shaft of the pattern-cylinder and the pawls that move them. Fig. 3 shows a section of the pattern cylinder and chain with a pair of the plate-levers that are operated by them. Fig. 4 is an end view of the parts shown in Fig. 3.

It will be seen by reference to Fig. 1 that the pattern mechanism has been changed from below the dobby-frame, its position in the patent before referred to, to a position on a level with the center pivots of the jack-levers, and that two ratchet-wheels H H', Fig. 2, are put on the shaft of the pattern-cylinder where one has heretofore been used, and two pawls K K' are employed to operate the ratchet-wheels. One of these pawls is pivoted to the rocker-lever B' below its

shaft T and the other pawl is pivoted to the rocker-lever above its shaft, by which it will readily be seen that one of the pawls moves the pattern-cylinder while the other 55 pawl is going back from having moved it. The result of this is that there are two short motions given to the pattern-cylinder—one by the inward movement of the upper part of the rocker-lever B and the other by the inward motion of the lower part of that lever. These two short motions equal in extent the one long motion formerly given by one pawl pivoted on one end of the rocker-lever, and the advantage gained by using the two short 60 motions is that whereas with one long motion it was necessary to indicate for two latch-hooks, an upper and a lower one, because both of them were likely to be required before another long motion of the pawl would 65 be made, with the two short motions it is only necessary to indicate for one latch-hook at each motion, thereby avoiding the trouble liable to be met with from indicating for a latch-hook before it was needed, as in case of 70 a positive-motion dobby the hook indicated in advance would be free of its check-bar and be liable to be moved by the friction of the harnesses in motion and the causes before the lifter moved it.

The plate-levers are in pairs, one of each pair to indicate for an upper latch-hook, which it raises by its inner end extended up for that purpose into contact with said upper latch hook, and the other for one of the lower ones, 75 which it operates by means of a wire connecting the lever with the hook, and one of each pair has the projection on its under side by which the pin in the pattern-chain raises it, placed just far enough in advance of the 80 like projection of the other one of the pair that as one row of pins raises one of a pair of levers the other one of the pair will be dropped by the row of pins just passed. This is shown in Fig. 3, where the pin o on the bar s has just 85 raised the lever F and the lever F' has just been dropped by the pin o' in the same bar. In addition to the greater security of the hooks already mentioned, I am enabled to shorten 90 the pattern-chain one-half in certain cases.

Owing to the limited space allowed for looms in mills, it is desirable to have all at-

tachments extend out from the body of the loom as little as possible. In attaching dob-
bies for weaving wide goods this is a serious
difficulty, as in the usual construction it is cus-
tomary to give a more extended motion to the
knives than in looms for weaving narrower
goods, in order to get sufficient motion to the
harness-levers. To obviate this extended
movement of the knives, the jack-levers can
be shortened to bring the point where the
power is exerted on the jack-lever nearer the
point where it is pivoted to the harness-lever; but in proportion as the jack-lever is short-
ened the rising movement of the lower end of
the jack-lever, which occurs when the latch at
the upper end thereof is engaged and moved
outward by the upper lifter, increases. This
upward movement of the jack-lever raises the
pivot end of the lower latch, and turning said
latch on the loop or bend of the wire, as on a
fulcrum, tends to lower the hooked end thereof
into engagement with the lower lifter and
thus occasion outward movement of said latch
and the lower end of the jack-lever with said
lifter at a time when such movement may not
be desired. To overcome this upward move-
ment, I make a projection D' on the jack-lever,
which projection has an opening therein
for the reception of the stud or pin g on the
harness-lever, which constitutes the pivot of
the jack-lever. This carries the center of
motion of the jack-lever out of line with the
end pivots of the latch-hooks, the effect of
which is to produce a falling movement of
the jack-lever while the upper end thereof
swings outward, and to prevent any upward
movement of the end of the jack-lever that
is in contact with its stop-bar.

Having thus described my improvements,
what I claim as my invention, is—

1. In a shedding mechanism for looms, a se-
ries of plate-levers arranged in pairs, one of
each pair having the projection by which it
is raised by the pins in the pattern-chain
placed in advance of the similar projection on
the other lever of the same pair, combined
with a pattern-chain cylinder provided with
mechanism for moving it to indicate for the
operation of the top and bottom hooks sepa-
rately, substantially as and for the purpose 50
specified.

2. In a shedding mechanism for looms, the
combination of a pattern-cylinder provided
with two ratchet-wheels, and two pawls to al-
ternately move the pattern-cylinder by en-
gagement with the said ratchet-wheels, with a
series of plate-levers arranged in pairs, one of
each pair having the projection by which it
is raised by the pins in the pattern-chain
placed in advance of the similar projection 60
on the other lever of the same pair, substan-
tially as and for the purpose described.

3. The combination, with a harness-lever, of
a jack-lever pivoted thereto and having latch-
hooks pivoted at the opposite ends of the same,
the pivot by which the jack-lever is connected
with the harness-lever being placed outside
of the line passing through the pivots of the
latch-hooks, as described.
